UNITED STATES PATENT OFFICE.

GEORGE HOVENDEN AND HIRAM A. HOVENDEN, OF PEORIA, ILLINOIS.

NAIL-EXTRACTOR.

SPECIFICATION forming part of Letters Patent No. 777,210, dated December 13, 1904.

Application filed February 20, 1903. Renewed October 4, 1904. Serial No. 227,163. (No model.)

To all whom it may concern:

Be it known that we, GEORGE HOVENDEN and HIRAM A. HOVENDEN, citizens of the United States, residing at Peoria, in the county 5 of Peoria and State of Illinois, have invented certain new and useful Improvements in Nail-Extractors; and we do hereby declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to nail-extractors, and particularly to that kind thereof in which the nippers are actuated by a lever to grasp the nail-head and draw the nail.

20 The object of the invention is to form an improved construction for grasping the head of the nail in the claws of the nippers and holding the same during extraction.

25 In the accompanying drawings, wherein the tool is illustrated, Figures 1 and 2 are side elevations of the tool in different positions. Fig. 3 is an edge view thereof.

30 Referring specifically to the drawings, the nipping-claws are indicated at 6 and 7. These are halved and lapped and pivoted together at 8 and normally separated by a coiled spring 14. The claw 7 has projecting therefrom a fulcrum-heel 9.

35 The stock 10 of the tool is pivoted at 11 to the upper end of the claw 7, which is split or grooved to receive the tongue 12, which extends within the groove and bears against the upper end of the claw 6. The upper end of the stock forms the anvil for a sliding hammer-handle 13 in a manner common to this 40 class of tools.

In operation the pressure of the spring 14 holds the jaws apart and the stock in alignment therewith, as shown in Fig. 1, in which position the claws may be driven into the wood beside a nail-head by strokes on the 45 hammer-handle. When the sidewise pressure is applied to extract a nail, the stock first turns on its pivot 11, causing the tongue to press outwardly against the top of the claw 6, bringing the jaws together to tightly clasp 50 the nail, after which the tool by continued pressure is caused to turn on the fulcrum-heel and lift the nail.

It will be seen that the initial pressure is directed to grasping the head of the nail, and 55 the lifting action does not take place until the nail is grasped as tight as possible. The tool is therefore free from the objection of slipping its hold.

What we claim as new, and desire to secure 60 by Letters Patent, is—

1. A tool comprising a pair of pivoted jaw members, a lever pivoted to the upper end of one member and bearing against the other, and adapted to close the jaws, and a spring 65 normally holding the jaws open and the lever in alignment therewith.

2. A tool comprising a pair of pivoted jaw members, a lever fulcrumed on one member and bearing at one end against the other above 70 the pivot, and a sliding hammer on the other end of the lever.

In testimony whereof we affix our signatures in presence of two witnesses.

GEORGE HOVENDEN.
HIRAM A. HOVENDEN.
